UNITED STATES PATENT OFFICE.

EMMA C. WOOSTER, OF NEW YORK, N. Y., ASSIGNOR TO JAMES V. ROCKWELL,
OF SAME PLACE.

DESIGN FOR RUCHES.

Specification forming part of Design No. 7,232, dated March 3, 1874; application filed January 31, 1874.
[Term of Patent 3½ years.]

CASE B.

To all whom it may concern:

Be it known that I, EMMA C. WOOSTER, of the city, county, and State of New York, have invented a Design for Ruches, of which the following is a specification:

The nature of my design is fully represented in the accompanying drawing, to which reference is made.

Figure 1 is a view in perspective of a ruche, made in accordance with my new design; Fig. 2, a transverse profile of the same.

Similar letters of reference indicate corresponding parts.

A represents the exterior, and B the interior, portions or borders of the ruche, both formed of ruffles or flutings, the transverse sections of which are of mainly curved, pear-

like, or elongated loop-like profile, as shown in Fig. 2, with rolling or rounded outer edges, and terminating at their inner edges in flattened continuations, and said ruffles or flutings lying back to back. Within the one of these ruffles or flutings, which is transparent, is a band or ribbon, C, of different color to that of the ruffle, the same extending longitudinally within the ruffle, and giving the appearance of a body-like filling thereto.

What I claim as my invention is—

The design for ruches, substantially as herein described and shown.

EMMA C. WOOSTER.
